UNITED STATES PATENT OFFICE.

EDGAR CARY, OF NEW YORK, N. Y.

MACHINE FOR FOLDING AND PASTING THE ENDS OF PAPER COLLARS.

SPECIFICATION forming part of Letters Patent No. 258,711, dated May 30, 1882.

Application filed February 14, 1882. (No model.)

To all whom it may concern:

Be it known that I, EDGAR CARY, a citizen of the United States, residing at New York, in the county and State of New York, have invented new and useful Improvements in Machines for Folding and Pasting the Ends of Paper Collars and other Articles, of which the following is a specification.

The object of this invention is to provide a machine in which the collars or articles to be folded and pasted are placed on endless belts or chains and carried over paste-disks and through the folding mechanism into a drying apparatus. This object I accomplish by 10 the construction and arrangement of mechanism illustrated in the accompanying drawings, in which—

Figure 1 is a section of my machine in the plane $\alpha \alpha$, Fig. 2. Fig. 2 is a plan view. Figs. 20 3, 4, and 5 are details.

Similar letters indicate corresponding parts.

In the drawings, the letter A designates the frame, on the upper ends of which are mounted the shafts a a' , carrying the rolls b b' , over 25 which pass the endless chains or belts c , which constitute the feed mechanism. These belts or chains, whose upper surfaces run flush with the table c' , have a series of small lugs, projecting upward, secured to them, so that when 30 a collar is laid on the table c' of the machine these lugs catch it and feed it along over the paste-disks and into the folding device.

The paste-disks d , Figs. 1 and 3, have the usual form with paste-surface just large 35 enough to supply the necessary quantity of paste to the inner surface of the collar, timed so as to put the paste in the proper place and receive their supply from paste-distributing roller e , which runs in the paste-trough f . The 40 distributing-roller e receives its motion through a belt, g , running over a pulley, h , mounted on the counter-shaft i , which has its bearings in the frame A. This counter-shaft has motion imparted to it by means of a belt, j , which connects it with the shaft a .

A belt or chain, l , which runs over the center of the roll b , Figs. 1 and 2, imparts motion to the folder-shaft m , on which are mounted the folder-cams n . These cams, which are situated one at each end of the folder-shaft m , are of the shape shown in Fig. 3, and are timed

to the motion of the chains or belts c , so that each half-revolution of the folder-shaft m the projecting parts o of the folding-cams n will bend down that part of the collar that is to be 55 folded in preparatory to passing through the sheet-metal folder p , which completes the fold. The form of this folder is shown in Figs. 3 and 4, and it is situated just beyond the folder-shaft m .

The collar-blank B, when it is placed on the machine, is of the form shown in Fig. 5. The flaps b^2 , while the collar-blank is being carried along by the belts or chains c and without arresting its motion, are first bent down at right 60 angles by the folder-cams n , after which it is carried through the sheet-metal folder p , where the fold is completed and the flap is bent under, as shown in dotted lines in Fig. 5.

The paste-disks d are secured to a shaft, d' , 70 which has its bearings in the frame A, and is geared to the folder-shaft m by gear-wheels d^2 d^3 , so that the paste-disks d and the folder-cams n always work together, being so adjusted that when the paste-disks have coated the flaps that 75 are next to be folded, and as the collars are brought under the folder-cams, the latter strike the flaps and fold them, as above described. Over the paste-disks d , but not so as to touch them or to come in contact with the paste on 80 them, are situated small friction-rollers q , which press on the flaps b^2 of the collar B as it is being coated with paste by the paste-disks d . These rollers turn on studs projecting from small angle-pieces, which are secured to the 85 guides r . These guides r , which consist of flat pieces of metal, are raised sufficiently from the table c' to permit the collars to pass under them, and are intended to keep the ends of the collars down on the chains or belts c as 90 the collars pass through the pasting and folding devices. $s s s$ are similar guides to keep the center of the collar down on the table c' .

The friction-rollers q and the paste-disks d are so placed in relation to each other that, 95 while the paste-disks revolve continuously, the friction-rollers turn only while a collar-flap is being coated with paste, when the collar-flaps, as they are being carried along by the chains or belts c , fill the space between the paste-disks 100 d and the friction-rollers q , causing the latter to turn, thereby fulfilling their purpose of

keeping the collar-flap in contact with the paste-disks only while it is being coated with paste, and then with the least possible friction.

What I claim as new, and desire to secure 5 by Letters Patent, is—

1. In a machine for folding and pasting collars, the combination, substantially as described, of the transverse shaft m , provided near each end with a folder-cam, n , with the 10 carrying belts or chains moving at right angles to said shaft.

2. In a machine for folding and pasting collars, the combination of the guides r , carrying rotary friction-rollers q , with the pasting-disks 15 d , arranged directly beneath the friction-rollers, the carrying belts or chains, and the trans-

verse shaft m , provided near each end with a folder-cam, n , substantially as described.

3. The combination of the transverse folder-shaft m , carrying near each end a folder-cam, 20 n , the transverse shaft d' , carrying paste-disks d and geared at one end with the folder-shaft, and the friction-rollers q , arranged directly above the paste-disks, substantially as described. 25

In testimony whereof I have hereunto set my hand and seal in the presence of two subscribing witnesses.

EDGAR CARY. [L.S.]
